(57) CLAIM

The ornamental design for a golf cart mirror as shown and described.

DESCRIPTION

FIG. 1 is a perspective view of a golf cart mirror according to our new design.

FIG. 2 is a front view of the golf cart mirror of FIG. 1.

FIG. 3 is a rear view of the golf cart mirror of FIG. 1.

FIG. 4 is a top view of the golf cart mirror of FIG. 1.

FIG. 5 is a bottom view of the golf cart mirror of FIG. 1.

FIG. 6 is a left side view of the golf cart mirror of FIG. 1; and,

FIG. 7 is a right side view of the golf cart mirror of FIG. 1. The features shown in broken lines form no part of the claimed design. It is intended that this disclosure includes support for amending any broken lines to solid lines or solid lines to broken lines so as to claim or disclaim, respectively, any part, portion, element and/or combination thereof of the disclosed design.
